PENDANT MOUNTING FOR LIGHTING FIXTURES AND THE LIKE

Edward B. Sperry, Fort Atkinson, Wis., assignor to Moe Light, Inc., Fort Atkinson, Wis., a corporation of Wisconsin

Application September 23, 1950, Serial No. 186,430

12 Claims. (Cl. 248—343)

1 This invention relates to a pendant mounting for lighting fixtures and the like. The invention contemplates means which is concealed in the ultimate position of the fixture and its canopy for the temporary pendant support of the fixture during the wiring thereof, such temporary support including links which are divergent so as to resist fixture displacement and which collapse into concealed positions within the canopy, the canopy and the mount for the links having detachable means for maintaining the assembly in its permanent position.

Principal objects of the invention include an arrangement whereby the divergent links collapse when the fixture is raised to its final position and include offsets for accommodating the permanent mounting pins, the links and mounting channel being wholly concealed within the fixture canopy in the elevated final position of the fixture.

In the drawings:

Fig. 1 is a view partially in side elevation and partially in longitudinal section showing a lighting fixture provided with a pendant mounting embodying the invention, the fixture being dropped to wiring position.

Fig. 2 is a view similar to Fig. 1 showing the parts as they appear when the fixture is elevated to its permanent position.

Fig. 3 is a view taken in section on the line 3—3 of Fig. 1.

Fig. 4 is a view on an enlarged scale taken in section on the line 4—4 of Fig. 2.

Fig. 5 is a fragmentary plane view of the assembled fixture and mounting, portions being broken away in horizontal section.

Fig. 6 is a view on a reduced scale showing in perspective a separated mounting and fixture.

The threaded stud 7 and nut 8 are used to connect the mounting channel 10 to the outlet box 9 in ceiling 11. The mounting channel 10 may be supported entirely by the stud 7 or it may receive its support from the screws 12 threaded into the ceiling, or both means of support may be used as shown.

The mounting channel 10 opens downwardly as best shown in Figs. 3 and 4, its central web 13 being desirably flat against the ceiling with the flanges 14, 15 depending therefrom. Suitable apertures are provided in the web 13 for the screws 12 and the thread 7 and for the admission through the channel of the electrical supply wires 16, 17 (Fig. 1).

The webs 14, 15 are provided near their ends with registering holes at 18 and inwardly from

2 the ends, the flanges have corresponding slots at 19.

The lighting fixture generically designated by reference character 20 has a canopy portion 21 with a downwardly channeled top wall 22 in the canopy portion. It is broadly immaterial to the present invention whether the canopy comprise a separate part, but it will be noted that the invention makes a separate canopy unnecessary. The width of the channel 23 in the top wall 22 is materially greater than the overall width of the mounting channel 10. There are openings 24 in the sides of the fixture which register with openings 25 in the channel walls 231 and 232 and are at spacings longitudinally corresponding to the spacing between the openings 18 in the supporting channel 10 fastened to the ceiling.

Links are used for the temporary support of the fixture from the supporting channel 10 during wiring. Each of these links may be made of wire of generally U-shaped form. The links are generically designated by reference character 30. Each has a transverse strand of wire 31 extending through the slots 19 of the mounting channel 10. From this depend the legs 32, 33 which are parallel at an overall spacing which is less than the total width of the channel 23 in the top member 22 of the fixture canopy 21. The legs 32, 33 have outwardly turned fingers 34, 35 at their lower ends which are engaged laterally in apertures in the side walls of the channel 23 of top member 22 of the light fixture canopy. It will be observed that the outermost ends of the respective slots 19 are spaced well inwardly from the holes 36, 37 in the canopy which are engaged by fingers 34, 35.

With the fixture depending from the mounting channel 10, as shown in Fig. 1, the links 30 are rather sharply divergent in an outward direction toward the ends of the fixture, thus tending to hold the fixture in a stable, non-swinging, position for the connection of its wires 38, 39 with the supply wires 16 and 17. During the making of the necessary connection, the entire weight of the fixture is suspended on the links 30.

When the wiring operation is complete, the fixture 20 is raised bodily, thus collapsing the links 30 and 31 and to the channel 23 of the top wall of the canopy and between the sides of channel 23 and the flanges 14, 15 of the channel-shaped mounting 10. The collapsed position of the links is clearly shown in Figs. 4 and 5. The collapse of the link 30 to the position indicated 55 is permitted by reason of the length of slot 19.

The lower and outer ends of the divergent links are at a fixed spacing in the holes 36, 37 of the canopy and consequently all of the displacement must be accommodated at the upper ends of the links, these being moved toward each other in slots 19.

When the fixture is moved to its permanent position with the top of its canopy in substantial contact with the ceiling, the holes 24 and 25 of the fixture canopy are registered with the holes 18 of the mounting channel and thereupon the mounting pins 40 are inserted through the registering holes in the manner shown in Figs. 4 and 5 to maintain the parts in assembly.

It will be observed that the mounting channel 10 is now entirely concealed within the canopy, being received bodily to the channel 23, together with the links 30 which provided a temporary suspension for the fixture during wiring. The only portions of the mounting equipment which 20 are visible are the pins 40. These may be so made as to be hardly perceptible.

It will be observed that in order that such pins may be received through the registering apertures of the fixture and the mounting channel, without interference with the links 30, it is desirable that the links be bent bodily as clearly shown in Figs. 1 and 2 so that in the collapsed positions of the links they will pass beneath the plane in which the pins are disposed. This would not be necessary but for the fact that in order to achieve compactness in the particular embodiment disclosed, the slots 19 of the mounting channels are located at one side of the pin-receiving apertures 18, while the fingers connecting the links with the fixture are located beyond the apertures 18 and, in fact, beyond the entrance of the mounting channel as a whole. This gives in limited space the desired outward and downward divergence of the links 30 when the links are in use, as shown in Fig. 1, and yet the angular offset of the legs of the links permits the links to collapse into the fixture chamber 23 without interference with the mounting pins 40 when the fixture is in its elevated position.

When the fixture is to be repaired or interchanged with another fixture, it is only necessary to withdraw the pin 40 in order to drop the fixture to the position shown in Fig. 1, where it is again supported on the links 30 with its wiring fully accessible.

The lower ends of the links have adequate flexibility so that they may be bent inwardly to disengage their fingers 34 and 35 from the aperture of the canopy to completely release the fixture from the mounting channel when desired. The links are simple flexed inwardly again when it is desired to reengage them with a correspondingly formed canopy of the same or a different lighting fixture.

Since the links are readily engaged singly and are adequate for the support of the fixture at all times during assembly or disassembly and wiring, and since the links remain available for this purpose in the concealed positions in which they are housed within the canopy, it will be apparent that the lowering and erection of fixtures of this sort has been greatly facilitated by the mounting means herein disclosed.

I claim:

1. A mounting device for the temporary and permanent support of a lighting fixture, said device comprising a mounting channel having means for fixing it to a ceiling, a canopy having

a connection with the fixture to be mounted and having a recess wider than the mounting channel to receive said channel telescopically in permanent support position, and links pivotally connected at spaced points with the mounting channel and the canopy and sharply divergent with respect to each other, whereby to provide stable, temporary support for the fixture from the mounting channel.

2. The device of claim 1 in which the links have yieldable free end portions with oppositely directed fingers for which the canopy has apertures, the said fingers being detachably engaged in the apertures.

3. The device of claim 2 in which the links comprise members engaging the mounting channels for which said channels are provided with longitudinally extending slots, the said link members being slidable in the slots upon collapse of the link into the recess of the canopy.

4. A mounting providing temporary and permanent support for a lighting fixture having a channeled canopy, said mounting comprising a mounting channel having means for ceiling support and being of materially less width than the canopy channel to be bodily received therein, the mounting channel having flanges provided with longitudinal slots, U-shaped links having transverse members slidably and pivotally mounted in the slots, and legs depending from said members and provided with laterally projecting fingers pivotally connected with the canopy, said links being collapsible into the canopy channel between the sides thereof and the flanges of the mounting channel.

5. A mounting providing temporary and permanent support for a lighting fixture having a channeled canopy, said mounting comprising a mounting channel having means for ceiling support and being of materially less width than the canopy channel to be bodily received therein, the mounting channel having flanges provided with longitudinal slots, U-shaped links having transverse members slidably and pivotally mounted in the slots, and legs depending divergently from said members and provided with laterally projecting fingers pivotally connected with the canopy, said links being collapsible into the canopy channel between the sides thereof and the flanges of the mounting channel, the said legs being sufficiently resilient to permit of the springing of the legs for engagement and disengagement of said fingers with the fixture canopy.

6. Means for the support of a fixture having a recessed canopy with spaced side walls providing pivot holes and mounting-pin holes, said supporting means comprising a channel bodily receivable into the recess of the canopy and provided with spaced dependent flanges having slots, links pivotally and slidably mounted in the slots and pivotally engageable in the pivot holes of the canopy, the said channel flanges having apertures with which the canopy mounting-pin holes are registerable, and mounting-pin means of a length and diameter to penetrate the mounting-pin holes of the canopy and mounting channels for the permanent support of the canopy.

7. In a device of the character described, the sub-combination which comprises a mounting channel provided with means for ceiling mounting and provided near its ends with mounting-pin holes and having slots inwardly of such ends, together with link means having leg portions collapsible alongside of the mounting channel, and cross portions slidably mounted in the slots, said

link means having free end portions adapted for detachable connection with a fixture to be mounted.

8. The device of claim 7 in which the respective link means comprise U-shaped members having transverse portions extending through said slots and provided at their free ends with outwardly bent fingers constituting said mounting portions adapted for fixture engagement.

9. The device of claim 8 in which the legs of the respective link means are bent intermediate their ends to clear the mounting-pin holes when the legs are collapsed externally of the mounting channel as aforesaid.

10. In combination a mounting channel comprising a central web having means for ceiling support and laterally spaced flanges depending from said web and provided near their ends with mounting-pin holes, and also having, inwardly of said holes, longitudinally extending slots, links, each comprising a U-shaped member having a transverse portion disposed in one of said slots, and legs spaced to be collapsed externally of the flanges and offset intermediate their ends to bypass the mounting-pin holes, each of said legs being provided at its free end with an outwardly bent finger for lighting fixture engagement.

11. The device of claim 10 including the combination with the lighting fixture having the canopy provided with a recess in which the channel and the legs of said links are bodily receivable,

the said canopy being further provided with side walls having apertures in which the fingers of said legs are engaged with the links at sharply outwardly divergent angles respecting each other, said walls further having apertures spaced inwardly from the apertures engaged by said fingers and registerable with the mounting-pin holes of the mounting channel, and mounting-pins movably disposed with registering apertures of the canopy and mounting-pin holes of the channel.

12. A mounting device for the temporary and permanent support of a lighting fixture, said device comprising a mounting channel having means for fixing it to a ceiling, a canopy having a connection with the fixture to be mounted, and collapsible links between said channel and canopy to temporarily support the canopy below said channel, said canopy having a recess wider than the mounting channel to receive telescopically and to conceal said mounting channel and said links in the permanent support position of the canopy.
